(57) **CLAIM**

The ornamental design for aquatic novelty, as shown and described.

DESCRIPTION

FIG. 1 is a top, front and side perspective view showing my new aquatic novelty design;

FIG. 2 is a top plan perspective view thereof;

FIG. 3 is a front perspective view thereof;

FIG. 4 is a side perspective view thereof, opposite to the side view shown in FIG. 1;

FIG. 5 is a rear perspective view thereof; and,

FIG. 6 is a bottom perspective view thereof, the broken line showing is for illustrative purposes only, and forms no part of the claimed design.
